UNITED STATES PATENT OFFICE.

PETER BROLIN, OF RANSOM, MICHIGAN, ASSIGNOR OF ONE-HALF TO JOSEPH H. EDINGER, OF SAME PLACE.

WRENCH.

SPECIFICATION forming part of Letters Patent No. 484,288, dated October 11, 1892.

Application filed May 31, 1892. Serial No. 435,018. (No model.)

To all whom it may concern:

Be it known that I, PETER BROLIN, a citizen of the United States, residing at Ransom Center, in the county of Hillsdale and State of Michigan, have invented certain new and useful Improvements in Wrenches; and I do hereby declare the following to be a full, clear, and exact description of the invention, such as will enable others skilled in the art to which it applies to make and use the same.

My invention relates to improvements in wrenches; and it consists of the combination, construction, and arrangement of parts, as will be hereinafter fully described and claimed.

To enable others to readily understand my improvements, I have illustrated the same in the accompanying drawings, in which—

Figure 1 is a plan view showing the same supported on the rail of a railway-track. Fig. 2 is a front elevation, part of the operating-lever being broken away. Fig. 3 is a side view of a modified construction of wrench. Fig. 4 is a sectional view on the line *x x* of Fig. 3, and Fig. 5 is a similar view on the line *y y* of Fig. 4. Fig. 6 is a detail view of one of the jaws of the wrench.

Like letters of reference denote corresponding parts in the several figures of the drawings, referring to which—

A designates the head of my improved wrench, which is provided at one end with a series of projecting fingers or prongs *a*, spaced and arranged so as to surround and bear closely against the sides of a nut, and the rear side or end of said head *A* has a stem or shank *a'*.

In Fig. 1 I have shown my wrench adapted for turning a nut on a bolt used to secure the fish-plate to the web of one rail of a railway-track. In this connection I employ a supporting-frame *B*, composed of two parallel side bars or members *b b*, provided near one end with the hooks *b' b'*, adapted to fit over or receive the head of a rail *C* and hold said frame in a horizontal position thereon. The bars *b b* are firmly secured on the rail by means of set-screws *b''*, working through said bars and bearing against the head of the rail, and said bars are connected by a cross bar or

c, which is rigid or integral with the side bars *b b*, and which is provided with a

suitable bearing to receive the outer end of the stem or shank *a'* of the wrench. On the stem of the shank *I* fit an operating lever or handle *D*, which is adapted to turn freely on 55 said shank and the lower portion of which is forked or bifurcated. To the stem or shank *a'*, between the forks of the lever *D*, I attach a ratchet-wheel *D'*, and within the forked end of the lever *D* are pivoted pawls *E*, the lower 60 ends of which are adapted to contact or engage with the teeth on the ratchet *D'*. The pawls *E* are normally pressed against the ratchet by coiled springs *E'*, inclosed within the lever *D* and operating to force the upper 65 ends of the pawls outwardly. On the side of the lever *D* is centrally pivoted a double latch or keeper *F*, the arms of which are bent near their outer ends so as to extend across the pawls or fingers *E* near the upper ends 70 thereof. By turning the latch or keeper *F* on its pivot the upper end of one of the pawls *E* will be forced inwardly, thus compressing the coiled spring in rear thereof and raising the lower end of said pawl out of 75 engagement with the ratchet *D'*. By raising and lowering the lever *D* the pawl which remains in engagement with the ratchet *D'* will at each upstroke of the lever turn said ratchet one tooth, and as the ratchet *D'* is 80 rigidly secured on the stem or shank *a'* of the wrench the nut engaged by the prongs *a* will be turned. By reversing the latch or keeper and forcing the previously-engaged pawl out of engagement with the ratchet *D'* the nut 85 can be unscrewed.

In the modified construction of wrench illustrated in Figs. 3 to 6, inclusive, the head *A* is composed of two pieces or sections *f f'*, each forming one side and a part of the top 90 and bottom, respectively, the two parts being secured together by screws or in any other suitable manner. In each side of the body is formed a longitudinal slot *G*, the sides of one of which are graduated. Within the head *A* 95 of the wrench are arranged the clamping-jaws *H*, and these jaws are provided in adjacent faces near their outer ends with recesses or sockets *h* to form teeth or biting-edges *h'*, and near their rear ends said jaws are reduced in thickness, such reduced ends being 100 lapped one upon the other and connected to

gether and to the head A by a bolt K, provided at one end with a nut L. Each of the jaws H is provided on opposite faces with a projecting guide pin or lug M, which pins fit in ways or grooves N, formed in the inner faces of the sides of the wrench-head. These grooves N connect with the longitudinal slots G at one end and diverge from their inner ends toward their outer ends. By loosening the nut L the bolt K can be moved forward in the slots G and the pins or lugs M, riding in the diverging grooves or ways N, cause the jaws to separate or move apart at their outer ends. When the jaws have been separated 15 or moved far enough apart to receive the nut or other object desired to be turned by the wrench, the nut L can be tightened and the jaws firmly held in the proper position. A ratchet and operating-lever similar to those shown in Figs. 1 and 2 is secured to the stem of the modified wrench just described.

I am aware that changes in the form and proportion of parts and details of construction of the devices herein shown and described 25 as an embodiment of my invention can be made without departing from the spirit or sacrificing the advantages thereof, and I therefore reserve the right to make such changes as fairly fall within the scope of the same.

To hold the jaw of the wrench firmly against the nut, I prefer to employ a coiled spring T, which is fitted around the stem or shank a' between the supporting-frame and the head 35 of the wrench, as shown in Fig. 1.

Having thus described my invention, what I claim as new, and desire to secure by Letters Patent, is—

1. A wrench consisting of a rigid head and 40 stem, a ratchet secured on the stem; an operating-lever fulcrumed on the stem and provided on opposite sides with pawls adapted to engage the teeth of the ratchet, and a latch or keeper pivoted on the lever and bent at

intermediate points of its length to pass 45 across the pawls, substantially as described.

2. A wrench consisting of a head, a stem rigid with said head, a bifurcated lever pivoted on the stem, a ratchet rigidly attached to the stem within the bifurcated end of the operating-lever, spring-pressed pawls pivoted within the bifurcated end of the lever and adapted to engage with the ratchet, and a latch or keeper centrally pivoted to one side of the lever and having its arms bent to extend over opposite edges of the lever and across the pawls on opposite sides of their pivots from the ratchet-wheel, substantially as described, for the purpose specified.

3. A wrench consisting of a hollow head provided with a longitudinal slot in opposite sides and having diverging grooves or ways formed in the inner faces of said sides, clamping-jaws pivotally connected together and provided with projecting pins or lugs which ride in the grooves or ways in the inner faces of the sides of the head, and means for moving the jaws longitudinally of the head, substantially as shown and described.

4. The combination, in a wrench, of the 70 sectional head provided with a longitudinal slot in opposite sides and having diverging grooves formed in the inner faces of said sides, the clamping-jaws having their inner ends reduced and lapped one upon the other and provided with projecting pins which fit in the diverging grooves in the head, a bolt extending through the slots in the sides of the head and the lapped ends of the clamping-jaws, and a nut fitted on one end of said bolt, substantially as described.

In testimony whereof I affix my signature in presence of two witnesses.

PETER BROLIN.
